UNITED STATES PATENT OFFICE.

AUGUSTUS T. JONES, OF STAMFORD, CONNECTICUT, ASSIGNOR TO STAMFORD FOUNDRY COMPANY, OF SAME PLACE.

DESIGN FOR DOUBLE PARLOR-HEATER.

Specification forming part of Design No. 7,885, dated November 24, 1874; application filed November 12, 1874.
[Term of Patent 7 years.]

To all whom it may concern:

Be it known that I, AUGUSTUS T. JONES, of Stamford, in the county of Fairfield and State of Connecticut, have invented a Design for Double Parlor-Heater, of which the following is a specification:

The nature of my design is fully represented in the accompanying photographic illustration, to which reference is made.

The design of heater is composed of an ornamentation of vertically-fluted work on the exterior of the ash-pit and the fire-box cylinders, in combination with a serpentine gas-chamber exterior, containing Norman-shaped openings, with beaded ornamentation around

the frames of such openings, and two cylinders above such gas-chamber, each containing a Norman-shaped door having an ornamentation of fluted work at the center and beaded work around the edge.

What I claim as my invention is—

A design for double parlor-heater in which the exteriors of the several sections and the doors of the double cylinder are ornamented substantially as described.

AUGUSTUS T. JONES.
